(57) **CLAIM**

The ornamental design for the street light cover, as shown and described herein.

DESCRIPTION

FIG. 1 is a front view of the street light cover;

FIG. 2 is a side view of the street light cover taken from any side of FIG. 1;

FIG. 3 is a back view of the street light cover; and,

FIG. 4 is a perspective view of the street light cover of FIG. 1 as mounted in a street light.

The broken lines shown in FIG. 4 are for representing environmental subject matter that forms no part of the claimed design.
